STAMP TAX DEVICE

William Berry White, Nashville, Tenn.

Application February 17, 1936, Serial No. 64,382

14 Claims. (Cl. 101—35)

The invention relates to new and useful improvements in printing machines generally, although more particularly to machines for stamping dates or other printed matter on the surfaces of packages, envelopes, and the like, in ink or otherwise, in a continuous and automatic manner, and the objects of the invention are particularly, first, to provide a machine that will properly and effectively and continuously affix 5 an authorized official tax stamp impression on individual packages of cigarettes, so that same may be permanently and undeniably affixed, thus eliminating the necessity of affixing independently a gummed stamped tax sticker; second, to provide a means for handling a large number 10 of packages rapidly and continuously; third, to provide a means of properly metering or counting said packages so that said stamping can be properly accounted for to the proper government officials; fourth, to provide a proper housing for the said mechanism to prevent tampering with the counting device so that only authorized persons may have access to the mechanism; fifth, to provide a means of permanently affixing 15 the stamped impression by heat applied concurrently with the impression.

With these and other objects in view which will more fully appear, the nature of the invention will be more clearly understood by following the description, the appended claims, and the several views illustrated in the accompanying drawings.

In the drawings:

Figure 1 is a front elevation of a printing machine embodying my invention, the front wall being broken away to disclose a mechanism located in rear thereof,

Figure 2 is a top plan view thereof,

Figure 3 is a vertical section taken on the line 3—3 of Figure 2,

Figure 4 is a left hand elevation, parts being shown in section,

Figure 5 is a detail sectional view of the printing mechanism,

Figure 6 is a perspective view of the stationary cam,

Figure 7 is a perspective view of the hopper, and

Figures 8, 9, and 10 are detail sectional views showing a modified form of counting mechanism.

Like reference numerals designate corresponding parts throughout the several figures of the drawings.

Referring to the accompanying drawings, my invention comprises a base 5 having a pair of spaced and upwardly extending parallel front and rear frame members or plates 6, 7 rigidly secured thereto. These plates are centrally 50 mounted on the base to provide spaces on the

base both in front of and in rear of the plates. The front space is closed by a vertical plate A having a front wall 8, end walls 9, 9, and inwardly extending rear end walls 10, 10. The front wall 8 and the end walls 9, 9 are rigidly secured to the base 5 and the rear end walls 10, 10 are rigidly secured to the ends of the rear frame plate 7. A top plate 11 is secured to the walls of the plate A and to the rear frame plate 7, and is provided with an opening 11^a located immediately in front of the rear frame plate 7.

Attached to the top plate in register with this opening is a hopper B into which cigarette packages C or other articles, which are to be printed, are first inserted and then ejected. This hopper includes a vertical plate which is bent to form side walls 12, 12, a rear wall 13 having a centrally located upstanding extension 14, and flanges 15, 16 which extend inwardly from the front edges of the side walls, the hopper being rigidly connected to the top plate 11 by brackets 17, 17. An inverted V-shaped partition 18 having upwardly inclined walls 19, 20 is centrally located between the side walls 12, 12 and is secured to the rear wall 13 and to the extension 14 thereof. The upper portion of the partition is narrower than the extension 14 and forms resultant flanges 21, 22 above the rear wall 13. The front edges of the partition walls 18, 18 are provided with laterally extending flanges 23, 24 which cooperate with the flanges 15, 16. Thus it will be seen that the hopper is divided by the partition to form a receiving compartment D and an exit compartment E, both of which are in register with the opening 11^a of the top plate 11.

The open front of the hopper B permits the operator to introduce the packages into the receiving compartment D and slip them downwardly in stacked relation. The flanges of the hopper cooperate with the packages both when the hopper is being loaded and unloaded, and the sloping partition facilitates either stacking a 40 number of packages in the receiving compartment D or allowing a number of stamped packages to accumulate in the exit compartment E.

Cigarette packages C are first placed in the receiving compartment D; they are then individually lowered through the opening 11^a; they are then moved individually and horizontally to a position under the exit compartment E and while being thus moved they operate a counter F; they are then individually subjected to a stamp printing action while at rest below the exit compartment E, and finally they are raised into the exit compartment E from which they are individually removed.

For the above purposes the following mechanisms are employed:

A transfer table G having low and high stepped portions 25, 26 is slidably mounted on spaced horizontal guide rails 27, 27 respectively supported on the frame members or plates 6, 7, the low portion or step 25 being normally below the receiving compartment D for receiving the lowermost package C as shown in Figure 3. An electric motor 28 which is mounted on the base 5 in rear of the frame member 7, drives a cross shaft 29 which extends across the frame members 6, 7 and is journaled therein. Preferably a reduction gear coupling 30 is positioned intermediate the motor shaft and said cross shaft. Fixed to the cross shaft 29 is a face cam 31 which is engageable with a roller 32 journaled in the lower end of an upwardly inclined lever 33 fulcrumed on a pivot shaft 34 secured to the frame members 6, 7 above and at the right of the cross shaft 29. The upper end of the lever 33 is connected by a link 33^a to the table G. A coil spring 35 is connected at one end to the lever 33 above its fulcrum and at its other end to a spacing element 36 which is disposed between the frame elements 6, 7, and serves to retain the roller 32 in engagement with the cam 31. Thus the table is intermittently reciprocated by the motor through the medium of the cam 31, the lever 33 and the spring 35. When the table has been moved to position a package C under the exit compartment E, the high step or portion 26 of the table will close the bottom of the receiving compartment D.

The counter F is mounted on the rear frame member or plate 7, and includes an operating lever 37 which projects forwardly through an opening 38 formed in said frame member 7 and into the path of transfer movement of the cigarette package C. The rear edge of the vertical wall 39 of the table G is provided with a slot 40 which registers with the lever 37 to thereby avoid the table engaging and operating said lever. Thus, when each package C is transferred from one position to the other by the table G, the counter F will be operated. A cover 41 and lock 42 are associated with the counter to prevent access thereto by unauthorized persons.

Located below and in alignment with the exit compartment E is a plunger elevator H for the packages C. This plunger includes a head 43 and an integral downwardly extending post 44 slidably mounted in a sleeve bearing 45 fixed to the rear frame plate 7. The lower end of the post is bifurcated to receive a roller 46 which is journaled on a bearing pin 47 fixed to the post. The post is normally held against upward movement by a coil spring 48 which is connected at its upper end to the post and at its lower end to the base 5. A cam-actuated bell crank lever 49 is fulcrumed on the pivot shaft 34 and includes a relatively short depending arm 51 and a relatively long horizontal arm 52, the end of the latter being disposed under and having contact with the roller 46. A roller 52^a is journaled on the lower end of the short arm 51 for engagement with a cam 53 fixed to the cross shaft 29. Thus, after the package C has been transferred by the table G, to a position under the exit compartment E and above the plunger H, the cam 53 functions to elevate the plunger and thereby project the package into the exit compartment E past spring retainers 54, 54 mounted on the walls of the compartment which function to retain the package against gravitating when the plunger is returned to its initial position.

When the package C is being transferred to a position above the plunger H, it contacts a cam projection 55 fixed to the frame member 7 and located directly below and centrally of the exit compartment E to thereby frictionally retain the package against the front frame member 6 and hold the package against movement when the low portion 25 is retracted upon the return movement of the table G.

The top plate 11 is provided with an opening 56 which extends forwardly from the exit compartment E, and supported on the top plate between the flanges 15, 23 of the hopper D is a vertically disposed plate 57 having a pad 58 secured to the front face thereof. Unwinding and winding spools 59 and 60 are respectively journaled on vertical shafts 61, 61 mounted on the top plate 11 on opposite sides of the opening 56. An inking ribbon or tape 62 is unwound from the spool 59 and wound onto the spool 60. This ribbon is fed over rollers 63, 63 mounted on the top plate 11 adjacent to but on opposite sides of the pad 58 whereby the ribbon is fed in a straight line and in a vertical plane directly in front of and in parallel relation to said pad.

In order to feed the ribbon, a horizontal shaft 64 is journaled in brackets attached to the front face of the front frame member 6 and is driven from the cross shaft 29 by a 1 to 1 gear coupling 65. A vertical shaft 66 is journaled in upper and lower bearing arms 67, 67 fixed to the front face of the front frame member 6 and is driven from the shaft 64 through the medium of a worm 68 fixed to the shaft 64 and a worm wheel 69 fixed to the shaft 66. Fixed to the upper end of the shaft 66 above the top plate 11 is a pulley wheel 70, and pivoted to the upper end of said shaft is an arm 71 having a pulley wheel 72 journaled on the outer end thereof. An endless feed belt 73 is trained around the pulley wheels 70, 72 and is held in frictional contact with the winding spool 60 by a coil spring 74 which has one end connected to the arm 71 and the other end to an arm 75 which is attached to the front frame member 6 and projects upwardly through an opening in the top plate 11. It will therefore be seen that the ribbon 62 is continuously fed from the spool 60, thence over one guide roller 63, thence in front of the pad 58, thence over the other guide roller 63, and thence to the spool 59.

An opening 76 is formed in the front plate 6 directly below the pad 58 and in front of the exit compartment E. A substantially horizontal tubular type arm 77 is located in register with the opening 56 and attached to the rear end of this arm is a type plate or printing die 78. The type arm is removably and adjustably mounted in a sleeve bearing 79 fixed to the upper end of a vertical type lever 80 which is located between the front frame plate 6 and the front wall 8 of the closure plate A. The type lever 80 is pivoted intermediate its ends as at 81 to a forwardly extending supporting lever 82 which extends above the shaft 64 and is pivoted at its rear end as at 83 on the frame plate 6.

Journalized on the supporting lever 82 directly above the shaft 64 is a roller 84. Fixed to the shaft 64 are three cams 85, 86, and 87, the cam 86 cooperating with the roller 84 to swing the lever 64 upwardly and thereby elevate the type arm 77 into position whereby the die 78 will later be moved to engage the inking ribbon 62.

The cams 85 and 87 are located on opposite sides of the cam 86 and respectively contact vertical followers 85^a and 87^a which are rigidly se-

cured to the lower arm of the type lever 80, and are held against the cams by a coil spring 88 which is connected at one end to the lever 80 and at the other end to the base 5. As soon as the type arm 77 has been elevated by the cam 86, the cam 87 functions to swing the type lever 80 to move the die 78 rearwardly against the ribbon 62 and pad 58 and thereby coat the die with ink. This contact of the die against the 10 ribbon and pad is of very short duration owing to the shape of the cam 87, and the lever is returned to its initial position by the spring 88. The continued rotation of the cam 86 then permits the type arm 77 and lever 80 to gravitate to 15 a position wherein the type arm can be projected rearwardly through the opening 16 in the frame plate 6 and contact the package C which is then in register with said opening. This rearward printing stroke of the type arm is brought about 20 by the cam 85 and the cooperating follower plate 85^a which swings the lever 80, the lever being then returned by the spring 88.

The cigarette packages C are enclosed in "Cellophane" wrappers and it is desirable to heat that 25 portion of the wrapper which receives the stamp. For this purpose, I have positioned an electric heating unit 89 in the tubular type arm 77 adjacent the printing die 78 whereby said die will be kept heated during the operation of the machine. Any suitable means may be employed for 30 retaining the heating unit in the type arm, and a flexible electric cord 90 is employed for conducting electric current to the unit.

In Figures 8, 9, and 10, I have illustrated another form of package counting mechanism which is particularly adapted for use in connection with a meter I now on the market. To this end, the cross shaft 29 is provided with a driving gear 91 which meshes with a gear 92 journaled on 35 the rear frame plate 7. A U-shaped frame 93 which supports the meter I is attached to the upper part of the frame plate 7 by rearwardly extending bolts having locking means 94 associated therewith, and a horizontal shaft 95 is 40 mounted in the frame 93 for rotation and also for endwise movement. Sprockets 96 and 97 are respectively fixed to the gear 92 and the shaft 95, and a sprocket chain 98 is trained around 45 said sprockets to drive the shaft 95 by means of which the counting of the packages is effected. Attached to the sprocket 97 to rotate therewith is a pulley 99 having a peripheral groove 100 and a rim 101, the rim being interrupted by a transverse space 102 forming a resultant beveled end 50 103 and square end 104 to the rim. A clutch lever 105 is fulcrumed on the frame plate 7 as at 106. The front arm 107 of this lever is disposed in front of the shaft 95 and a pin 108 is pivotally connected to the rear arm 109 thereof. 55 A flat spring 109^a is attached to the U-frame 93 and engages the rear arm 109 of the clutch lever for urging the pin 108 inwardly in the groove 100 and for yieldably retaining the front arm 107 against pressing the shaft 95 rearwardly. 60 The meter shaft 110 is disposed in alignment with the shaft 95. A disc 111 is secured to the end of the meter shaft 110 and is provided with a circular recess 112. A disc 113 is securely attached to the disc 111 and is provided with a 65 forwardly extending pin 114, the disc 113 forming the bearing for the rear end of the shaft 95. A rearwardly extending pin 115 is secured to the sprocket 97.

In operation, the sprocket 97 is rotated by the

motor, and when a package C is being transferred to its printing position, it actuates the clutch lever 105 which moves the pin 108 outwardly and the shaft 95 rearwardly towards the meter I, the end of the shaft moving into the recess 112. This movement effects a clutching action between the pins 108 and 115 whereby the meter shaft 110 is rotated for one revolution. At the same time, the rim 101 is moved rearwardly and the pin 108 is caused to ride on said rim.

If the packages are being fed to the machine continuously, the operation of this registering device will be such that the two pins 114 and 115 will be continuously engaged and the pin 108 will be riding the rim continuously. Should, however, a package be missed, or the machine be in operation with no packages passing through, after a count has been registered, a further slight rotation of the grooved pulley will bring the space 102 to the pin 108, and the said pin 108 will drop off the square end 104 into the space 102, a further rotation of the shaft 95 causing the beveled edge 103 of the rim to strike the pin 108, and as the rotation proceeds the beveled edge 103 of the rim will pull the shaft 95 and its connected parts back to the original position, and on the next revolution of the shaft 95 the pin 115 will pass by the pin 114 and a count will not be registered. The slot 40 of the table G permits this table to pass by the clutch lever 105 without engaging the same. The advantages of this form of clutch mechanism to connect with the standard meter are apparent from the fact that in its normal operating position it does not register a count while the machine is running, if no package is passing through, but if any attempt is made to tamper with the clutch lever 105, or the protruding end of the shaft 95, the clutch mechanism will be set in operation to engage the pins so that a count will be registered. If any attempt is made to hold the clutch lever down by some unlawful means the positive action of the device will at once cause it to count. The device illustrated is a typical form, and it is understood that a variation of the sprocket and chain drive, such as a gear-train, or other methods of securing the device to the machine frame may be adapted to this particular invention without affecting the validity of the device itself.

It is of course to be understood that the details of structure and arrangement of parts may be variously changed and modified without departing from the spirit and scope of my invention.

I claim:

1. In a package printing machine, the combination with a receiving compartment and an exit compartment, of a table for transferring a package from a position below the receiving compartment to a position below the exit compartment, means for printing the package while it is at rest below one of said compartments, and means for projecting the printed package into the exit compartment.

2. In a package printing machine, the combination with a receiving compartment and an exit compartment, of a table for transferring a package from a position below the receiving compartment to a position below the exit compartment, means for reciprocating said table from one position to the other, means for printing the package while it is at rest below one of said compartments, and means for projecting the printed package into the exit compartment.

3. In a package printing machine, the combination with a receiving compartment and an

- exit compartment, of a table for transferring a package from a position below the receiving compartment to a position below the exit compartment, means including a cam actuated lever and link for reciprocating said table from one position to the other, means for printing the package while it is at rest below one of said compartments, and means for projecting the printed package into the exit compartment.
4. In a package printing machine, the combination with a receiving compartment and an exit compartment, of a table for transferring a package from a position below the receiving compartment to a position below the exit compartment, a reciprocatory plunger for transferring the article from the table into the exit compartment, and means for printing the package when it is below the exit compartment and above the plunger.
5. In a package printing machine, the combination with a receiving compartment and an exit compartment, of a table for transferring a package from a position below the receiving compartment to a position below the exit compartment, means for reciprocating said table from one position to the other, a reciprocating plunger for transferring the article from the table into the exit compartment, and means for printing the package when it is below the exit compartment and above the plunger.
6. In a package printing machine, the combination with a receiving compartment and an exit compartment of a table for transferring a package from a position below the receiving compartment to a position below the exit compartment, a reciprocatory plunger for transferring the article from the table into the exit compartment, means for frictionally retaining the package below the exit compartment and above the plunger, and means for printing the package while so retained.
7. In a package printing machine, the combination with a frame including a base and spaced vertical plates and a top, the latter having an opening communicating with the space between the plates, of a hopper mounted on the top and including receiving and exit compartments registering with said opening, a table slidably supported on the plates below the top for transferring a package from a position below the receiving compartment to a position below the exit compartment, a reciprocatory plunger for transferring the package from the table into the exit compartment, a reciprocatory printing device for printing the package when it is below the exit compartment and above the plunger, a motor mounted on the base, and operating means for the table, the plunger and the printing device supported on the frame plates and operatively connected to the motor.
8. In a package printing machine, the combination with a receiving compartment and an exit compartment, of a table for transferring a package from a position below the receiving compartment to a position below the exit compartment, counting mechanism operated by the package while the latter is in transit from one position to the other, means for printing the package while it is at rest below one of said compartments, and means for projecting the printed package into the exit compartment.
9. In a package printing machine, the combination with a hopper having a receiving compartment and an exit compartment, of a table for transferring a package from a position below the receiving compartment to a position below the exit compartment, counting mechanism including a lever operated by the package while the latter is in transit from one position to the other, means for printing the package while it is at rest below one of said compartments, and means for projecting the printed package into the exit compartment.
10. In a machine for printing packages wrapped in "Cellophane", the combination with means for transferring the package from one position to another, of means for printing said package when it is in one of said positions including a type arm having a wrapper-engaging die, and means for heating said die.
11. In a machine for printing packages wrapped in "Cellophane", the combination with means for transferring the package from one position to another, of means for printing said package when it is in one of said positions including a reciprocatory type arm having a wrapper-engaging die, and means for continuously heating said die.
12. In a package printing machine, the combination with a hopper having a centrally located and inverted V-shaped partition forming resultant receiving and exit compartments, of a table for transferring a package from a position below the receiving compartment to a position below the exit compartment, means for printing the package while it is at rest below one of said compartments, and means for projecting the printed package into the exit compartment.
13. In a package printing machine, the combination with a hopper comprising a back wall, side walls and flanges extending inwardly from the edges of the side walls, the back wall having an upwardly projecting and centrally located extension, an inverted V-shaped partition centrally positioned with respect to the side walls to form resultant receiving and exit compartments, the partition projecting above said back and side walls and being centrally located with respect to the extension of the back wall to form resultant flanges, and flanges projecting inwardly from the partition and arranged in alignment with the flanges of the side walls, of a table for transferring a package from a position below the receiving compartment to a position below the exit compartment, means for printing the package while it is at rest below one of said compartments, and means for projecting the printed package into the exit compartment.
14. A machine invented for the purpose of stamping cigarette packages with an official tax stamp, consisting of the combination in such a machine of a sealed case, housing a reciprocally movable feed table, with a reciprocating return table, a hopper for receiving and discharging the packages, having a double sloping partition, with opposite sides cut lower than the height of the partition, an oscillating die head for producing an impression of the tax stamp, means for heating said die, a means of feeding an inked ribbon with which to ink the face of the die, a means of automatically registering the number of packages passing through the machine, a suitable reducing gear for driving the machine at any desired speed, and a motor, to supply power.
